UNITED STATES PATENT OFFICE.

MAY C. MABEE, OF TOLEDO, OHIO.

MACHINE FOR TREATING MATERIALS.

Application filed September 11, 1915. Serial No. 50,224.

To all whom it may concern:

Be it known that MAY C. MABEE, a citizen of the United States, residing at Toledo, in the county of Lucas and State of Ohio, has 5 invented certain new and useful Improvements in Machines for Treating Materials, of which the following is a specification, reference being had therein to the accompanying drawing.

- 10 This invention relates to an apparatus for treating liquid or substances containing liquid to change the condition or consistency thereof, and while susceptible of a wide range of uses, it is one of the primary 15 objects of the invention to provide a novel apparatus for the treatment of material with a view to rapidly evaporating therefrom, in whole, or, in part, the liquid contained therein.
- 20 One of the primary features of the invention involves means for forming and maintaining under circumferential movement a layer of material on the interior surface of a vertically disposed cylindrical container, while maintaining a central zone for the evaporating gases, and permitting the material to gradually flow from one end of the container to the other.

In the art to which the present invention 30 relates, it has largely been the practice to treat substances, such as milk, by causing the material to move through a closed cylindrical container, the wall of which is subjected to a heating medium. These containers 35 have been arranged both horizontally and vertically, and in that type of apparatus employing the vertically disposed container, it is customary to feed the material into the container at the base thereof and cause 40 the same to move upwardly under centrifugal force to be discharged through an outlet at the top of the container. In an apparatus of this type, it has been ascertained that, owing to the unequal pressure, and the 45 force of gravity, the layer of material would gradually taper from a very thin film adjacent the top of the container to a relatively wide layer at the base thereof, and because of the thin film of material adjacent the 50 top of the container, a very high temperature could not be transmitted to the treat-

ing surface, in view of the likelihood of scorching or burning the material at this point.

By the present invention, it is contemplated to provide means whereby a vertically disposed cylindrical container may be utilized and whereby the wall of the container may be subjected to a high temperature, associated means being provided whereby the layer of material in its movement through the container will be substantially uniform throughout and subjected to substantially the same treatment and temperature effect from end to end of the container.

In the embodiment of the invention herein disclosed, provision is made of a substantially cylindrical container for the material to be treated, said container being arranged substantially vertically and having external means for applying to the wall thereof a temperature different from that of the material to be treated, and means for feeding the material into the container at or adjacent the top thereof and discharging the same at the base, the material in its passage assuming a circumferential movable film or layer formation on the interior surface of the container, and an opening being provided at one or both ends of the container for the escape of vapor and gases.

Another feature of the invention includes means within a vertically disposed container of the character just described for moving, spreading and more equally distributing material upon and circumferentially over the inner surface of the container as moved downwardly along said surface.

It has been ascertained that by introducing the material at the top of the container and spreading the same in thin film or layer formation over the inner surface thereof, it is possible to, in a very economical manner, cause rapid evaporation or change in the condition or consistency of the material, and to, at the same time, overcome to a considerable degree the possibility of the coagulation of solids etc. due to the application of excessive heat for a prolonged period of time.

In the treatment of fluid or substances containing fluid, it is found that where the

treating surface is arranged horizontally, or where the material is introduced at the base of the vertically disposed container, centrifugal force must be largely depended upon for forcibly projecting the material onto and over the surface and through the container, whereas in the present embodiment of my invention, the material is caused to gradually flow downwardly over the inner surface of the container, as a result of the pull or attraction of gravity, the downward movement being sufficiently retarded by the natural force of adhesion to said surface, and by movable means within the container, to enable complete treatment of the material prior to its discharge at the outlet end of the container.

The natural power of adhesion is of high importance in the treatment contemplated herein, as it enables a thin sheet, film or layer of liquid to be moved rapidly over a treating surface without expending the force necessary to maintain it against the treating surface, and because of the fact that the liquid adhering to the treating surface can be moved thereover, while in a very thin film or layer, the treatment will necessarily be quite rapid.

It is also contemplated by the present invention to provide means whereby the material at its entrance to the container will be more evenly distributed circumferentially and with this in view, I preferably provide at the inlet end of the container a plurality of closely associated openings arranged in series circumferentially of the wall of the container, thereby providing in effect a substantially continuous circumferential inlet for the material.

Still another feature of the invention includes means whereby the temperature regulating medium may have imparted thereto a sinuous or helical course of travel, which is useful in connection with certain treatments wherein it is desirable to impart different temperatures to different portions of the treating surface.

Other and further improvements and novel details in the construction and arrangement of parts will be appreciated from the description to follow, when considered in connection with the accompanying drawings which for a part hereof, and wherein is disclosed for the purpose of illustration convenient and satisfactory embodiments of the invention, though it is to be understood in this connection that various changes may be made within the scope of the invention without departing from the principles thereof.

In the drawings,

Figure 1 is a vertical section of the apparatus,

Figure 2 is a transverse horizontal section,

Figure 3 is a detail view in section of a

modified form of conveyor or spreader member.

With more particular reference to the drawings, wherein like reference numerals refer to corresponding parts throughout the several views, 1 is a vertically disposed container, the cylindrical wall of which is provided with a surrounding jacket 2 of greater diameter, whereby to provide an intervening space 3 for the reception of a heating medium. The jacket 2 is conveniently offset at its upper and lower edges so as to provide circumferential bands 4 contacting with the outer surface of the cylindrical wall of the container and secured thereto, as by removable screws or bolts 5. A collar 6 is also secured as by bolts 6^a to the outer surface of the cylindrical wall of the container above the jacket 2, said collar having an outwardly flared portion 7, so as to provide with the cylindrical wall of the container at its top, an annular receptacle or trough for the reception of material to be fed into the container for treatment. The cylindrical wall of the container at a point adjacent the lower edge of said trough is provided with a circumferential series of openings 8, preferably disposed inclined, and adapted to provide an inlet for the material from the trough at various points about the circumference of the treating surface, provided by the cylindrical wall of the container. Of course, the number of inlet openings may be varied, but it is preferred that these openings be closely associated throughout the entire circumference, and if desired, in some instances a continuous annular or circumferential inlet may be provided in lieu of the series of openings, since in either case a substantially continuous circumferential inlet for the material may be provided and the material will be substantially equally distributed entirely around the upper edge of the treating surface.

The material as delivered into the container through the openings 8 will flow downwardly by force of gravity over the surface of the container, and owing to the force of adhesion due to the viscosity of the fluid this downward movement will be slightly retarded. It is desirable that the material as it flows through the openings 8 be spread in film formation circumferentially over the treating surface of the container, and with this in view means are positioned within the container having movable members adjacent said treating surface whereby to wipe or spread the material circumferentially over said surface, and whereby to assist in maintaining the material in circumferential layer formation in its movement both circumferentially and longitudinally of the container. This means is conveniently constructed as follows: 9 is a ver-

tically disposed shaft arranged substantially centrally of the container and having a loose bearing 10 in the base or bottom wall 11 of the container. The shaft 9 at one end, 5 conveniently the upper end thereof, projects beyond the adjacent end wall of the container, and has secured thereto a suitable pulley 13, adapted to have movement transmitted thereto through the medium of a belt or the like 14. In this connection, it may be observed that any suitable driving means for the shaft may be provided, but at the same time this driving means should be of a character so as to impart to the shaft a rotation 10 at a high speed, say from 300 or 400 revolutions or more per minute. Suitable webs or supports 15 are secured to the shaft, two being preferably provided adjacent opposite ends thereof at points within the container, 15 which said supports have connected thereto in any desired manner vertically extending angle bars or the like 16 adapted to support wipers of flexible material 17, the latter being secured as by plates 18 and removable bolts 19 the plates 18 reinforcing the wipers at their points of connection, and the bolts permitting the wipers to be removed and replaced as desired.

The wipers in the rapid movement over 30 and preferably in contact with the treating surface, will serve to evenly spread or distribute the material as delivered into the container circumferentially over the treating surface of said container.

The angle bars 16 and associated parts adjacent the upper end of the container are preferably bent inwardly, as indicated at 20, so that in the rotary movement thereof, the inwardly bent parts will act as abutments and tend to impart to the material a downwardly moving tendency, in addition to the natural flow of gravity.

The cylindrical wall of the container terminates at its lower end in an inwardly and upwardly curved wall 21 forming an annular receiving chamber 22 for the treated material, from which receiving chamber the material finds an outlet through the opening 23 into a suitable conduit 24 or the like, leading to a suitable receptacle or the like. The opening 23 and conduit 24 may be tangentially arranged, if desired.

The operation being such that a movable cylindrical layer of the material is maintained in contact with the treating surface, a central quiet zone for the escape of gases or vapors from said layer is provided centrally thereof, and a free escape therefor is preferably arranged on both ends of the container. In the embodiment of the invention herein, the outlet for the vapors and gases is provided in a removable top wall 25, the said top wall having an opening 26 in communication with an outlet conduit 27, leading to the outside, or in case it is desirable

to utilize the escaping gases and vapors for other purposes such as in obtaining a multiple effect, said vapors and gases may constitute the heating medium for succeeding effects.

It is obvious of course that because of the fact that the material preferably flows downward in thin layer of film formation in contact with the inner surface of the cylindrical wall, and readily finds escape through the outlet opening 24, in the base of the container adjacent the periphery, it is possible to provide for the escape of vapors at the lower end as well as the top of the container. To this end, one or more openings 21' are provided at the base of the container, it being noted that said base is substantially free of the material, the enlarged annular chamber 22 taking care of any possible temporary accumulation of material at this point.

A suitable antifriction bearing for the shaft 9 may be provided as follows:

The top or cover 25 for the container is conveniently provided with an annular way 29 for the reception of a series of balls 30, 90 a collar 31 secured to the shaft 9 having a similar annular way to engage the opposite surface of the balls.

The heating medium is introduced into the passage 3, as through the inlet conduit 95 or pipe 32 preferably by being blown therein. The space 3 is preferably provided with spirally arranged deflectors or walls 33. The heating medium, such as steam, is introduced into the space 3 through the conduit 32 preferably in a tangential direction, and the spiral walls or partitions guide the same in a helical direction towards the outlet end of the space, the outlet being indicated at 34. It will thus be appreciated that the heating medium slightly varies from the inlet to the outlet and the heat will be somewhat reduced at the outlet end of the container. It will also be noted that the helical arrangement of deflectors affords 100 a runway for any water of condensation, and the latter will have a tendency to rapidly flow along the runway thus provided, to the outlet 34 rather than cling to the side wall of the cylindrical container, 110 which would retard the heat transmission.

It should also be noted that the conveyor or wiper members may take various forms, and in that embodiment illustrated in Figure 3 these members take the form 115 of angle bars 35 projecting longitudinally of the container and adjacent the treating surface.

The container may be supported in any desired manner as by suitable standards 125 36. The operation may be briefly reviewed as follows: Assuming that the apparatus is to be utilized for the purposes of evaporation and that milk is the material to be treated, the same is fed into the annular 130

receptacle or trough at the top of the container through the conduit 37 or the like from any suitable supply, and continuously fed into the cylinder through the apertures 8, substantially entirely around the wall of the container. As delivered to said surface, the conveyor or spreader members tend to spread the material over the inner surface of the wall of the container, and when the wipers 7 are utilized, the latter will serve to constantly cleanse and polish the surface, as well as convey the material circumferentially. Because of the peculiar formation of the upper ends of the conveyor members, the movement of the milk is allowed a downward tendency upon its entrance into the container and will continue to flow downwardly by force of gravity, and owing to the rapidly moving conveyor members, this downward flow is impeded and the material will be caused to assume a continuous circumferentially movable film or layer formation in contact with the inner wall of the treating surface. The milk as treated will find an outlet at the base of the container, as at 24, and the vapors and gases which pass into the quiet central zone within the layer of material will find free exit through the outlet 26 at the end of the container.

While the material being treated in the operation of the apparatus has been referred to as milk, it is to be borne in mind that the present apparatus is quite useful in connection with the heating or pasteurization of juices of fruits and various other materials or products, and because of the fact that the material is fed into the container at the top thereof, a very thin and substantially uniform layer of material from top to bottom is made possible, thus resulting in a very rapid treatment of the material. The thinner the body of material subjected to treatment, the more rapid will be the evaporation or change in condition or consistency thereof.

It is found that in the treatment of materials such as milk, juices of fruits, and the like in the apparatus herein described, it is possible to utilize as the heating medium, steam at a very high temperature; in fact, a temperature from 212 up to as high as 300 or 400 degrees F. without any possibility of burning or scorching.

While the operation of the construction as described may be said to have more particular reference to evaporation, at the same time, it is to be noted that the structure is clearly applicable and serviceable in connection with the heating, pasteurization or otherwise treating various materials and substances to change the condition or consistency thereof, and whereas certain figures may have been referred to as relating to the preferred speed of the wiper members

81, or the temperature of the heating medium, it is to be noted that these figures are illustrative only as referring more particularly, to evaporation, and the speed of rotation of the wipers as well as the temperature of the heating medium may be varied according to the desired treatment of the particular material operated upon. It has been found possible to so treat the material as to reduce the same to a powdered consistency, as well as to pasteurize and evaporate.

I claim:

1. In an apparatus for treating liquids or substances containing liquid the combination of a substantially vertically disposed cylindrical container, means for heating the wall of the container, said container having at one end adjacent the periphery thereof an inlet and an outlet adjacent the opposite end, means co-operating with said surface whereby the material to be treated from its point of introduction to its discharge is permitted to move circumferentially and longitudinally of the container while maintained in film or layer formation adjacent the inner surface of said wall of the container, and said container having an opening in opposite ends thereof for the free escape of vapors and gases from the central space within the film or layer.

2. In an apparatus for treating liquids to change the condition thereof, the combination of a vertically disposed cylindrical container having an inlet for the material to be treated adjacent the top thereof, and an outlet adjacent the bottom thereof, means for exteriorly heating the peripheral wall of the container, rotatable yieldable means for engaging the material, applying the same in circular layer formation on the inner surface of the container and moving the same circumferentially while permitting the material to move longitudinally downward towards the outlet, and said container having openings in opposite end walls thereof for the free discharge of the vapors and gases.

3. In an apparatus for treating material to change the consistency thereof, the combination of a vertically disposed cylindrical container, means for heating the wall thereof to a high temperature, said container having in its periphery adjacent the top thereof a substantially continuous circumferential inlet for the material to be treated, means whereby the material is allowed to flow downwardly over the inner surface wall of the container while maintained under positive circumferential movement over said wall in layer formation, and means whereby the vapors and gases are allowed to escape from the central zone within the layer of material outwardly through opposite ends of the container.

4. In an apparatus for treating liquid substances to change the consistency thereof, the

combination of a vertically disposed cylindrical container, means for imparting to the surface of the container, a temperature different from that of the material to be treated, means whereby a substantially unbroken continuous circular layer of the material is maintained in operative relation to the treating surface and subjected to continuous uninterrupted circumferential movement there-

over and simultaneous lengthwise movement 10 in the same direction from its point of entrance to its point of discharge, said container being open at opposite ends for the free discharge of vapors and gases.

In testimony whereof I hereunto affix my signature.

MAY C. MABEE.
